RUG HOOK

Filed July 5, 1932

FIG. 1

FIG. 4

FIG. 2

FIG. 3

BY

John P. Tibbutt

U.S. Charles

ATTORNEY.

UNITED STATES PATENT OFFICE

JOHN P. TIBBUTT, OF BLACKWELL, OKLAHOMA

RUG HOOK

Application filed July 5, 1932. Serial No. 620,779.

My invention relates to an improvement in a rug hook.

The object of my invention is to provide a hook mechanism operative from the finished face of the rug.

A further object of my invention is to provide a hook mechanism that will receive the yarn in its open position whereby the usual method of threading an eye or slot is avoided.

A still further object of my invention is to provide a hook mechanism having a pair of arms pivotally connected and a hook on the outer end of each that seat together terminating into one point for simultaneous penetration of woven fabric.

These and other objects will hereinafter be more fully explained, reference being had to the accompanying drawing forming a part of this specification and in which like characters will apply to like parts in the different views.

Referring to the drawing:

Fig. 1 is a side view of the hook mechanism in operative position engaged with the fabric fragmentarily shown.

Fig. 2 is a transverse view of Fig. 1, the fabric illustration being omitted.

Fig. 3 is a side view of the hook mechanism drawing a loop through the fabric.

Fig. 4 is a diagrammatic drawing of a rectangular portion of woven fabric having a design stamped thereon preparatory for execution by filling in with yarn or the like with the rug hook.

My invention herein disclosed consists of a rug hook comprising an arm 1 having a hook 2 on the extreme outer end thereof and an arm 3 having a hook 4 on the outer end likewise. The other end of each arm has a looped handle portion 1' and 3' integral therewith. The said handles with their respective arms are pivotally connected as at 5 by which means the hook elements through manipulation of the looped handles are moved to and from each other.

As a means to automatically move the said hooks from each other I have placed a spring element 6 between the handles, each end of which seats in a groove 7 on the inner

side of each of their respective handles, and being so arranged the said spring is easily removed and replaced. At the pivot point 5 the arm and handle portions are halved together as shown in Fig. 2 by which arrangement shoulders A and B will contact when the hooks are moved to their extremity from each other. When the said arms are brought to a closed position as shown in Fig. 3, the point of hook 4 will seat within the barbed portion of hook 2 as shown at C, surface aligning the same by which means the said points will penetrate through fabric without interruption and being so arranged the said arms 1 and 3 are spaced apart forming an elongated slot in which the yarn is positioned as means to draw the same in looped form D as drawn through the woven fabric E. It will be understood that the barbed portion of each hook is the catch to carry the yarn through the fabric to an extent desired and will release the same when the said hooks are moved from each other. While I have shown and described yarn as the pile constructing element, I do not wish to have it understood that such alone may be employed as other strands such as strips of cloth or other fabrication may be employed in like manner.

The method of operation is as follows: In hooking a rug I take a piece of burlap or other fabric placing the same well tensioned within a frame and mark or stamp a design thereon, as shown in Fig. 4 for example. It is possible however, to obtain such fabric stamped with ornamentation. To perform the work I engage the loops of the handle with the thumb and preferably the forefinger, as means to move the arms toward each other and when closed the points are inserted through the fabric to the extent approximately as shown in Fig. 1, and permit the arms and their respective points to move from each other by actuation of spring 6, I then place therebetween the yarn as shown at D' in said figure, and closing the arms as previously described, the said yarn is retained and carried by the said hooks upward through the fabric to the extent de-

sired as a pile for the rug that is being hooked. It will be understood that the yarn is guided to engagement with the hooks on the under side of the fabric by the other hand and by which art of performance designs may be carefully followed with one color of yarn and filled in there around with another color as a field or background for the ornamentation, and at all times the operation of hooking is performed from the face of the rug or the like and the fingers not engaged for the manipulation of the rug hook mechanism may remain in contact on the rug as the said mechanism is inserted and retracted through the fabric reciprocatingly while the other hand is engaged with the yarn to position the same within the control of the hook arrangement.

Such modifications may be employed as lie within the scope of the appended claims. Having fully described my invention what I claim as new and desire to secure by Letters Patent is:

1. In a rug hook mechanism, a pair of arms pivotally connected, each arm having a looped handle and a spring positioned between the handles to rock the same outward, a pointed and seated hook element on the other end of one of the arms and a pointed hook element on the other end of the other arm, the said hook portions directed toward each other and adapted to engage and space the said arms apart in parallelism when rocked to a closed position for the purpose specified.

2. In a rug hook mechanism, a pair of arms having a handle integral with each, and a hook on the other end of each arm, the barbed portions thereof being directed toward each other, a seat on one hook to receive the point of the other hook in surface alignment, the barbs to function as means to space the arms apart.
